UNITED STATES PATENT OFFICE.

EMMA POYER, OF LOS ANGELES, CALIFORNIA.

GARMENT.

1,380,589.

Specification of Letters Patent. Patented June 7, 1921.

Application filed September 30, 1919. Serial No. 327,538.

To all whom it may concern:

Be it known that I, EMMA POYER, a citizen of the United States, residing at Los Angeles, in the county of Los Angeles and 5 State of California, have invented a new and useful Garment, of which the following is a specification.

This invention relates more particularly to a "one-piece" garment of a type especially suitable for nurses and others desiring to wear a garment that is comfortable to work in and one that at the same time is fitted more or less to the body so as to present a neat appearance.

15 An object of this invention is to produce a garment of this description which will fit loosely enough to permit of comfort to the wearer and at the same time will fit sufficiently close at the waist to give somewhat 20 the appearance of a house or street dress.

Other objects and advantages will appear in the subjoined detailed description.

The accompanying drawings illustrate the invention:

25 Figure 1 is a front elevation of a garment embodying the invention.

Fig. 2 is a side elevation of the garment.

Fig. 3 is a rear elevation of the garment.

30 Figs. 4, 5 and 6 are sectional plan views on lines indicated by x^4-x^4 , x^5-x^5 and x^6-x^6 respectively, Fig. 3.

There are provided front pieces 1, 2 and a back piece 3 joined by seams 4 to the front pieces so as to form a "one-piece" garment.

35 Fastened at its opposite ends by stitches 5 to the front pieces 1, 2 is a belt 6. The belt is also fastened intermediate of its ends to the back piece 3 by the stitches 5. The back piece 3 is provided with a box plait 7 secured by the stitches 5 of the belt.

40 From the belt 6 downwardly for a slight distance the box plait 7 is secured or held in by stitches 8, and said box plait is loose above the belt as indicated at 9 and gradually disappears toward the neck and is loose below the stitches 8 as indicated at 10 and gradually disappears toward the hem of the garment. It is thus clear that the

45 back piece is gathered in somewhat at the waist so as to fit closely to the wearer, and that the box plait is free from fastening above the belt and somewhat below the belt to permit the garment to expand at the back.

The side portions of the fronts 1, 2 are 55 provided with plaits or folds 11 which are secured or held in at the belt by the stitches 5. The folds 11 are loose above and below the belt as indicated at 12, 13 and gradually disappear toward the neck and hem of the 60 garment. The folds 11 being free from fastening excepting at the belt permits the garment to expand at the sides above and below the belt to give freedom of movement to the wearer.

65 Fastening means 14 are provided to connect the front pieces 1, 2 to each other. The ends of the belt are spaced from each other so that the front pieces hang straight and loose.

70 From the foregoing description of the invention it will be seen that, while I have employed certain devices well known in the dressmakers' art, the particular combination utilized produces a new result and gives 75 a pleasing effect to the eye as well as comfort to the wearer even though she be employed in the various duties incumbent upon the nurse.

I claim:

80 In a garment, front pieces, a back piece fastened to the front pieces, and a belt fastened at its opposite ends to the front pieces and fastened intermediate of its ends to the back piece, there being folds in the 85 front pieces respectively fastened only at the belt and gradually disappearing toward the neck and hem of the garment, and there being a box plait in the back piece fastened at the belt and for a slight distance below the belt and loose above the belt and somewhat below the belt and gradually disappearing toward the neck and hem of the garment, and the belt having its ends spaced apart and the front pieces hanging 90 straight and loose.

95 Signed at Los Angeles, California, this 24th day of September, 1919.

EMMA POYER.
